DRYING METHOD AND MACHINE

Ralph C. Parkes, Glenside, and David H. Colker,
Philadelphia, Pa.

Application January 28, 1947, Serial No. 724,903

4 Claims. (Cl. 34—33)

This invention relates to a drying method and machine in which, and to a method of drying by which, the drying potential of the drying medium and the contact of the drying medium with the materials or objects to be dried may be accurately controlled and varied according to the size, shape, moisture content, or the drying characteristics of such materials or objects so as to obtain maximum uniformity, speed and efficiency in the drying of said materials and objects and to eliminate, or, at least, greatly reduce losses due to damage which may otherwise result from lack of control, or from improper control of any of the factors enumerated.

It is, of course, appreciated that each class of objects presents minor problems peculiar to it, but it is believed that the accurate control and adjustment of the drying potential as well as its distribution according to the nature, size, shape and drying characteristics of the objects to be dried, are fundamental to, and underlie, the drying of most, if not all, kinds of objects or materials. Therefore, while the invention is applicable to the drying of all kinds of materials and objects, it is especially valuable for the drying of ceramics and other synthetic or natural objects and materials where the rate at which the objects or materials are dried and where the uniform drying of various parts of such objects and materials are critical.

Taking ceramics as a representative example, it is noted that the drying of this class of objects, prior to firing, presents exceptional difficulties. This is due to the fact that a wet ceramic or other object contains shrinkage water (which is in the nature of a film of water disposed between the grains of which the object is formed, and the removal of which causes the object to shrink), and pore water (which is in the nature of moisture carried in the pores of the grains, and which remains in the body of the ceramic object after perceptible shrinkage has ceased but before the drying operation has been completed).

As a ceramic or other object is dried, evaporation first takes place at the surface thereof, and the removal of shrinkage water causes the grains in the exterior layer to come closer together, thus shrinking the exterior of the object. Obviously, if the drying and consequent shrinking of the exterior of the object is rapid enough, relative to the drying and corresponding shrinking of the interior thereof, visible or invisible cracks may result, or deleterious strains may be set up within the body of the object.

Also, when in drying a ceramic object, the ex-

terior of the object is dried rapidly relative to the drying of the center thereof and the grains of the exterior layer move close together, the capillary network within the interior of the object is interrupted. This makes the center-to-surface diffusion of the residuary water (be it shrinkage water or pore water) very slow and difficult and thus greatly retards the drying process if cracking and other defects are to be avoided.

This invention, therefore, still further relates to improved apparatus for, and method of, drying ceramic objects at a relatively rapid rate, while eliminating or greatly reducing development of cracks and other defects.

Ceramics have heretofore been dried by means of different kinds of driers and according to different processes, one of which is a continuous process drying carried out in a tunnel-type machine. In this type of drying, the objects to be dried are placed in or propelled through, an enclosure of the desired length, and are subjected to the continuous action of a fluid drying medium, such as air, having the desired heat and moisture content. An example of this type of drying is one in which the drying medium is discharged, under more or less pressure, from one or more nozzles located in or near the plane of one of the vertical side walls of the enclosure.

By this arrangement, the proximal side of the object, that is, the side thereof facing the nozzles, will be subjected to the predetermined drying potential of the drying medium as it emanates from the nozzles, while the distal side of the object will be subjected to the drying medium after its drying potential has been reduced by contact of the drying medium with the proximal side of the object. Obviously, the opposite sides of the object cannot be simultaneously uniformly dried, and if cracking and other damage is to be avoided, an object so dried must be dried at a very slow rate and, hence, inefficiently and at an increased cost.

This invention, therefore, still further relates to an improved continuous or non-continuous chamber, or tunnel-type, drier in which the drying medium can always be applied directly to at least two or three sides of an object to be dried, such, for example, to the sides and top, or to the bottom and/or sides of an object whereby all parts of said object may be dried with sufficient uniformity so as to eliminate or greatly reduce the development of cracks and other defects.

The difficulties above suggested are especially acute in the case of objects having non-sym-

metrical contours, because, if such objects were dried according to conventional practice, and at a rate consistent with efficient operation, considerable losses would be incurred due to cracking or other defects resulting from non-uniform drying of such objects. If the drying operation is slowed down enough to prevent or reduce losses due to cracking, strains, etc., there will be considerable increase in costs due to inefficient operation of the drying apparatus.

This invention, therefore, still further relates to an improved, tunnel-type, drying apparatus, whereby non-symmetrical ceramic and other objects can be uniformly dried at a rate consistent with efficient operation of the apparatus while eliminating or reducing cracking and other defectives.

These and other objects are attained by this invention as set forth in the following specification and as illustrated in the accompanying drawings, in which:

Fig. 1 is a fragmentary and diagrammatic top plan view of a drying machine embodying the invention.

Fig. 2 is a side elevational view of the machine looking in the direction of line 2-2 on Fig. 1.

Fig. 3 is a vertical sectional view taken on line 3-3 of Fig. 1.

Fig. 4 is an enlarged fragmentary view looking in the direction of line 4-4 on Fig. 3.

Fig. 5 is an enlarged fragmentary view looking in the direction of line 5-5 on Fig. 3.

Fig. 6 is an enlarged, fragmentary view looking in the direction of line 6-6 on Fig. 2.

Fig. 7 is a diagrammatic view looking in the direction of line 7-7 on Fig. 3, illustrating the manner in which the flow of air is reversed relative to the objects being dried according to the improved method forming part of the invention.

Fig. 8 is a fragmentary enlargement showing details of construction of the air nozzles.

Fig. 9 is an enlarged fragmentary view, showing details of construction.

Fig. 10 is a top plan view of Fig. 9 looking in the direction of line 10-10 on Fig. 9.

In the drawings, and as shown in Fig. 1, there is illustrated a tunnel-type drying machine composed of a plurality of sections or self-contained units A, B, C, etc. Each of the units includes a wall structure defining a drying chamber 10, a source of heat 12 and a variable pitch, reversible blade blower 14 for drawing or blowing air over or through the source of heat and circulating the air through the drying chamber. While it is conceivable that any single unit can be used independently, it is the practice, in order to take advantage of continuous process operation, to use a plurality of sections A, B, C, etc., placed in alignment so as to form a tunnel of the desired length. The sections A, B, C, etc., may each comprise a single drying chamber 10, so as to form a single-lane tunnel, or, preferably, each section will have a plurality of drying chambers 10 and 10a, etc., disposed side by side to form a multi-lane tunnel, as best shown in Figs. 1 and 3.

Extending through each lane of the tunnel is a monorail 16 on which travels pendant racks 18. Each rack 18 preferably carries a plurality of superimposed perforated trays or the like 20 and 21 for carrying ceramic or other objects 22 and 23 to be dried. At the opposite ends of the tunnel, there are provided vacant chambers 24 and 26 which are closed by hinged doors 27, and through which racks may be fed into, or withdrawn from the adjacent tunnel chambers with

minimum loss of heat. For example, if it is assumed that the racks 18 move from left to right as viewed in Fig. 1, the chamber 24 at the feed end of the tunnel and the chamber 26 will be at the discharge or delivery end of the tunnel.

The pendant racks 18 may be driven through the tunnel by any suitable means, but in the preferred form disclosed, each of the lanes 10 and 10a of the tunnel is provided with a worm 30 which is driven by a source of power, such as a motor M, and each of the racks is provided with a pair of shoes 32 which are threaded and shaped to engage the upper portion of the worm so as to propel the racks along the monorail when the worm is turned. Since the rate of movement depends on the pitch of the worm thread and/or on the speed or rotation of the worm, the rate of movement of the racks 18 may be regulated as desired.

When the tunnel is relatively short, the worm may be made in one piece, but, when the tunnel is long, the worm preferably is made in sections joined together, or if it is in one piece, the thread is interrupted at intervals and the worm is supported at these intervals by means of journal bearings 33 carried by pedestals 34, as shown in Fig. 2. It will be noted that the journal bearings are slightly below the axis of the worm and that the gearing 35, intermediate the worm and the shaft of the motor M, is likewise below the worm. Since the shoes 32 engage only the upper portion of the worm and since the journal bearings engage only the lower portions of the worm, the provision of the bearings does not interfere with the progress of the racks 18 along the monorail. It will be noted that the shoes 32 are spaced so that each rack has one shoe near its leading edge and the other shoe near the trailing edge thereof. By this arrangement, added stability is attained and the racks are continuously propelled because, as the leading end of a rack is passing over one of the journal bearings, the rack will continue to be propelled by the shoe at the trailing end thereof, and vice versa.

In order to expedite loading and unloading, means has been provided for readily engaging the shoes 32 with, and disengaging them from, the worm so as to permit quick feeding of the racks into and quick withdrawal of the racks from the chambers 24 and 26, respectively. In other words, if the doors at the feed or delivery end of the machine are to be opened, and kept open, while the racks are slowly moved into or out of the feed and delivery chambers of the tunnel by the action of the worm, there will be considerable loss of heat and time. But, by providing means for disengaging the shoes 32 from the worm, the racks can be rapidly placed in the loading chamber 24 and can equally rapidly be removed from the unloading chamber 26. This means, as best shown in Fig. 6, includes a lever 40, which is fulcrumed at 42 and pivoted at 44 to arms 46, which carry the shoes. When the lever 40 is depressed to the dotted-line position of Fig. 6, the shoes are raised out of engagement with the worm. Therefore, when loading the tunnel, the accessible lever 40 on any given rack is depressed to raise the shoes 32, the rack is placed on the monorail and pushed into the feed chamber 24 as far as there is room, and the lever 40 is then raised to lower the shoes 32 into engagement with the worm to cause the rack to be propelled by the worm. Similarly, when the racks reach the delivery chamber 26, the shoes 32 are disengaged, and the

racks are quickly pulled off the monorail. In other words, the levers for engaging and disengaging the shoes on any rack are connected in tandem so that, by operating the lever 40 at the leading, or at the trailing, end of a rack, both of the shoes carried by said rack are actuated. This permits disengagement of the shoe at the trailing end of a rack when the leading edge thereof becomes accessible through the end chamber 26, and vice versa. Also, by this arrangement, the time during which the doors 27 are kept open during the loading and unloading is greatly shortened.

Each of the tunnel units A, B, C, etc., is provided with a compartment 50 which houses the variable-pitch, reversible-blade blower 14, the source of heat 12, and, where desirable, a humidifier 54. The compartment 50 is provided with an air inlet 56 controlled by adjustable louvers 58, and a controlled air exhaust 60.

The chamber 50 communicates at its top with a plenum chamber 64 which overlies the lanes 10 and 10a of the adjacent tunnel unit. The chamber 50 also communicates at its bottom with a compartment 65 which underlies, and communicates, with the interior of the lanes 10 and 10a.

The air delivery by the blower is selectively directed, by means of turning vanes 66 and 67, into the upper ends of juxtaposed pairs of vertical ducts 68 and 70, as shown by the arrows 69 and 71, respectively. The ducts 68 and 70 are provided with oppositely-facing, vertically-spaced nozzles 74 which extend substantially the entire length of the drying chamber and which direct the drying air against the opposite sides of the objects carried by the racks 18, or across the path of movement of said objects, as shown by the arrows 75.

It will be noted that each of the lanes 10 and 10a is provided with its own drying air supply directly from the main source so that the drying potential in these lanes can be maintained at substantially the same value. This makes it possible, simultaneously, to dry as many objects, or as many series of objects (having substantially the same drying characteristics) as there are lanes. Also, by varying the volume, and/or velocity of the drying medium from one lane to another, it is possible, simultaneously, to dry objects having different drying characteristics.

In order to subject various portions of the objects 22, 23, etc., to the predetermined drying action of the heated air as it emanates from the nozzles, the nozzles are slanted in the direction of movement of the objects, as diagrammatically shown in Fig. 4 so that, as an object progresses past the tier of nozzles, different portions thereof will be successively exposed to the direct blasts of air issuing from the nozzles. For example, as the object 22 moves from left to right, successively higher portions thereof will register with, and will receive air from, successive, corresponding portions of the juxtaposed nozzles, until, when the object 22 has reached its extreme right-hand position, the top of the object, which was well above the highest nozzle portion as it entered the drying chamber, will be below the corresponding nozzle portion. In other words, the nozzles are so arranged relative to the objects on the racks 18 that successive portions of the objects are successively subjected, but only for relatively short periods of time, to the direct action of the air as it flows from the nozzles, and the remaining portions of the object, for the rest of its travel through the particular drying chamber, are en-

veloped by air, the drying potential of which has been reduced by its initial contact with various parts of the object.

This arrangement plays an important part in preventing, or minimizing, cracking and other defects which may result from conventional drying and, at the same time, by making for more uniform drying, permits speeding up of the rate of drying. For example, if portions x and z of object 22 are subjected to the action of air as it flows from the nozzles during the entire travel of the object through the tunnel, while other portions of the object are only subjected to the drying action of air which has already come in contact with the portions x and z of the object, the portions x and z will (a) dry more rapidly than the remaining portions, thus setting up strains and possible warping, (b) dry more rapidly than corresponding interior portions, thus causing cracking, and (c) lose their surface shrinkage water, thus breaking up the capillary action and retarding center-to-surface diffusion of residual shrinkage and pore water. But, by subjecting successive portions of the object, as it passes through a drying chamber, and for brief periods, to the drying air as it emerges from the nozzles, and then subjecting all parts of the object to the action of the diffused air, the difficulties above set forth are wholly, or at least to a great extent, overcome.

The nozzles 74 may be spaced and slanted in the successive tunnel units, as shown in Fig. 4, or the spacing and slanting may be almost infinitely varied, as shown in Fig. 5, for example, so as to adapt the distribution of the drying medium to the various shapes of any number of different objects having non-symmetrical contours. For example if the object bulges out laterally, so that portions thereof are very close to one or both of the corresponding nozzles, while other portions of the object recede and are relatively remote from the corresponding nozzle, the flow of air will be regulated accordingly, either by omitting or partially or wholly closing a nozzle or more at one point, and by opening wide, or by increasing the size or number of the nozzles at another point. This can be done by providing the nozzles with adjustable shutters 82, as shown in Fig. 8, or the nozzles can be built in banks having different arrangements (as to slanting and non-slanting, and as to size and number and direction of nozzles), and the banks of nozzles can be made bodily removable so that, when drying a job lot of one type of object, one set of nozzles will be used, and, when drying a job lot of another type of object, a different set of nozzles will be substituted.

In the drying of certain types of ceramic and other objects, it may be necessary, or desirable, to humidify the drying air so as to retard surface drying while the temperature of the interior of the object is being raised to a value which will insure substantially uniform drying of the exterior and interior of the object. In such cases, the relative humidity may be controlled by varying the proportion of outside air admitted through the louvered inlet 56, or the humidifier 54 may be used as and to the extent indicated, it being noted that, as the drying progresses, the relative humidity of the drying air is progressively lowered.

While satisfactory drying may be achieved by the means thus far described, the invention also contemplates provision of one or more pendant nozzles 78 which may be used for directing heated air directly toward the upper surface of the ob-

ject 22 on the upper tray 20, as best shown in Fig. 3. The nozzles 78 may converge, vertically speaking, so as to direct the air delivered therethrough directly onto the top of the object, thus minimizing the interference of the downward blast of the nozzles 78 with the horizontal blasts of the nozzles 74. The nozzles 78 are also preferably provided with adjustable louvers 82, like those shown in Fig. 8, for regulating the flow of air as may be desired.

Since, as shown in Fig. 3, the air is delivered to the ducts 68 and 70 through the upper plenum 64 and since all of the air delivered to a tunnel unit is withdrawn through the lower compartment 65, it follows that the lower portion of a single, vertically-extending object 22 and the lower object 23 of a plurality of superposed objects, will be subjected to the drying action of the air directed laterally thereagainst through the adjacent nozzles, as well as to the drying action of such air as was initially directed against the upper portion of a single vertically-extending object 22, or against the uppermost object 22 of a plurality of superposed objects. In other words, an object near the lower portion of a tunnel unit will be subjected to the drying action of all of the air delivered to such unit, while an object near the upper portion of a tunnel unit is subjected only to the action of the air blown directly thereagainst. When it is remembered that the air in the upper portion of the tunnel is that which is delivered by the upper nozzles while the air in the lower portion is a mixture of the air delivered through the lower nozzles and the air which has already come in contact with the object 22 in the upper portion of the tunnel unit, it will be seen that the drying potential in the lower portion of the tunnel unit will be different from the drying potential in the upper portion of the tunnel unit. This condition is somewhat undesirable when two superimposed objects 22 and 23 are being dried and is aggravated when a greater number of superimposed objects are to be dried simultaneously. Thus, if the racks 18 should be provided with three or more vertically-spaced trays, each of which supports one or more objects to be dried, the differential between the drying conditions prevailing in the uppermost and lowermost portions of the tunnel unit will be correspondingly increased.

In order to overcome this difficulty, the present invention contemplates intermittently reversing the relation or direction of movement of the drying medium relative to the superimposed objects in the various tunnel units. This is done by delivering air to one tunnel unit, horizontally, from nozzles in the vertical side walls thereof, and/or downwardly through nozzles in the top of said unit, and then withdrawing all of the air delivered to said unit through the bottom of such unit, as shown in Fig. 3, and by delivering air to another tunnel unit, horizontally, through nozzles in the vertical side walls and/or upwardly through nozzles in the bottom of such unit and then withdrawing all of the air delivered to said said other unit through the top thereof.

For example, and designating the various tunnel units shown in Fig. 7 by the letters D, E, F, and H, it will be seen that, in the unit D, the blower 14, turning vanes 66 and 67, the nozzles 78, when used, and the heaters 12 are arranged, vertically, in the order shown in Fig. 3. In the next unit E, the blades of the blower are reversed so as to blow air downwardly, and at least the turning vanes 66 and 67, and the nozzles 74

are associated with the lower compartment 65 so that it now becomes the plenum, and the upper compartment 64 will receive the return air. If desired, the heaters 12 may also be moved to a position between the blower and the upper compartment 64 as it is preferable to draw, rather than to push, the air through the heaters. In the unit F, the parts are again arranged, as in Fig. 3, and in the unit H, the parts are again 10 reversed, the same as in the unit E and so on.

By this arrangement, the flow of the drying medium is intermittently reversed, that is, downwardly past one or more vertically-disposed objects 22 and 23 in one drying chamber, or tunnel unit, and upwardly past said objects in another tunnel unit, thus insuring more uniform drying of the upper and lower portions of a single, vertically-extending object and more uniform drying of a plurality of vertically-spaced or superimposed objects.

In the drying of objects having complementary, complicated and highly non-symmetrical contours, it may be desirable to rotate the objects being dried as they move through the drying chamber so as more effectively to expose the various portions of the objects to the drying medium. For example, and as diagrammatically shown in Fig. 9, the racks 18 which support the objects to be dried, are pivoted as at 86, so as 25 to be freely rotatable, and are provided with gears 88 which, as the racks 18 move through the drying chamber, engage a toothed rack 89. By this, or any other suitable means, the trays 30 and 21 and the objects 22 and 23 thereon are 35 rotated about vertical axes as they move horizontally through the drying chamber or chambers. Obviously, with a slight change of the parts, the objects can be made to rotate about horizontal axes, if so desired.

Having described the invention, what we claim is:

1. The method of drying a ceramic object or the like which method consists in moving said object through a plurality of longitudinally aligned enclosures, discharging individual streams of a fluid drying medium from opposite sides of said enclosures onto opposite sides of said object, exhausting said drying medium through the upper portion of one of said enclosures, and exhausting said drying medium through the lower portion of another of said enclosures.

2. A drying machine for drying a ceramic object or the like said machine including an elongated drying chamber, means for propelling an object to be dried through said chamber, and means for delivering individual streams of a fluid drying medium horizontally from opposite sides of said chamber, there being an exhaust outlet 55 near the top of one portion of said drying chamber, and an exhaust outlet near the bottom of another portion of said chamber.

3. A drying machine for drying a ceramic object or the like, said machine including an elongated chamber, means for propelling a plurality of superimposed objects through said chamber, means for delivering individual streams of a fluid drying medium from opposite sides of said chamber onto opposite sides of said objects, as they move through said chamber sections, there being a first outlet opening near the bottom of one of section, through which said drying medium is exhausted, whereby, as said objects move through said one section, the lower of said objects, and the lower portions of the upper of

said objects, will be subjected to the action of the drying medium directed thereagainst, as well as to the action of the drying medium directed against the higher portion of said upper objects, there being a second outlet opening near the top of another section of said chamber through which said drying medium is exhausted from said other section of said chamber, whereby, as said objects move through said other section, the upper of said objects, and the lower portions of the lower of said objects, will be subjected to the action of the drying medium directed thereagainst as well as to the action of the drying medium directed against the lower portions of said lower objects.

4. The structure recited in claim 3 together with means for supplying drying medium downwardly through the first mentioned section and means for supplying drying medium upwardly through the second mentioned section.
